(45) **Date of Patent:** **** Nov. 26, 2024**

(54) **SENSOR**

(71) Applicant: **MediBeacon Inc.**, St. Louis, MO (US)

(72) Inventors: **James Harr**, Wentzville, MO (US);
Lester Paul Trelford, St. Louis, MO (US); **Daniel Dion**, Rochester, MN (US); **Robert Kent Payne**, Woodbury, MN (US)

(73) Assignee: **MEDIBEACON INC.**, St. Louis, MO (US)

(**) Term: **15 Years**

(21) Appl. No.: **29/869,661**

(22) Filed: **Jan. 6, 2023**

(51) LOC (14) Cl. **10-07**

(57) **CLAIM**

The ornamental design for a sensor as shown and described.

DESCRIPTION

FIG. 1 is a perspective view of a sensor showing the new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

In these drawings, the solid lines illustrate the claimed ornamental design, whereas the broken lines illustrate unclaimed environmental features and form no part of the claimed design.
